US00D779804S

(12) **United States Design Patent** (10) **Patent No.:** **US D779,804 S**
(45) **Date of Patent:** **** Feb. 28, 2017**

(54) **FOOTWEAR OUTSOLE**

(71) Applicant: **Deckers Outdoor Corporation**, Goleta, CA (US)

(72) Inventor: **Jennifer MacIntyre**, Santa Barbara, CA (US)

(73) Assignee: **Deckers Outdoor Corporation**, Goleta, CA (US)

(**) Term: **15 Years**

(21) Appl. No.: **29/548,849**

(22) Filed: **Dec. 17, 2015**

(51) **LOC (10) Cl.** **02-04**

(52) **U.S. Cl.**

USPC **D2/960**; D2/951; D2/953

(58) **Field of Classification Search**

USPC ..... D2/902, 906, 916, 918, 925, 946–962, D2/977; 36/1, 1.5, 3 B, 22 R, 24.5, 25 R, 36/28, 32 R, 34 R, 59 C, 67 A, 101–107, 36/114–116, 117.3, 117.4, 124–136

(57) **CLAIM**

The ornamental design for a footwear outsole, as shown and described.

DESCRIPTION

FIG. 1 is a perspective view of a footwear outsole showing my new design;

FIG. 2 is a bottom plan view thereof;

FIG. 3 is a top plan view thereof; and

FIG. 4 is a side elevational view thereof;

FIG. 5 is an opposite side elevational view thereof;

FIG. 6 is a front elevational view thereof; and,

FIG. 7 is a rear elevational view thereof.

The broken lines in FIGS. 1-7 represent portions of the footwear that form no part of the claimed design. The broken lines which define the bounds of the claimed design form no part thereof.

1 Claim, 6 Drawing Sheets
